UNITED STATES PATENT OFFICE.

SIGMUND L. LEDERER, OF PROVIDENCE, RHODE ISLAND.

DESIGN FOR A COMBINED LEATHER AND METAL FABRIC WATCH BRACELET.

Application filed August 1, 1922. Serial No. 3,264. Term of patent 7 years.

To all whom it may concern.

Be it known that I, SIGMUND L. LEDERER, a citizen of the United States of America, residing at Providence, county of Providence, State of Rhode Island, have invented a new, original, and ornamental Design for a Combined Leather and Metal Fabric Watch Bracelet, of which the following is a specification, reference being had to the accompanying drawing, forming a part thereof.

The figure is a face view of a combined leather and metal fabric watch bracelet, illustrating my new design.

I claim:

The ornamental design for a combined leather and metal fabric watch bracelet, as shown.

SIGMUND L. LEDERER.
